UNITED STATES PATENT OFFICE.

ALBERT SCHMIDT, OF FLINT, MICHIGAN, ASSIGNOR TO CHAMPION IGNITION CO., OF FLINT, MICHIGAN, A CORPORATION OF MICHIGAN.

SPARK-PLUG.

1,077,002.

Specification of Letters Patent.

Patented Oct. 28, 1913.

Application filed May 1, 1911. Serial No. 624,335.

To all whom it may concern:

Be it known that I, ALBERT SCHMIDT, a citizen of the United States of America, residing at Flint, in the county of Genesee and State of Michigan, have invented certain new and useful Improvements in Spark-Plugs, of which the following is a specification, reference being had therein to the accompanying drawings.

10 This invention relates to improvements in spark plugs and more particularly to means for detachably connecting electrical conductors to such devices.

15 The object of the invention is to provide a simple and efficient device for the purpose which may be quickly and easily attached to or detached from the spark plug and forms a closure for the upper end of the plug having a lateral lead which may be 20 rotated to any desired position, the invention consisting in the matters hereinafter set forth and more particularly pointed out in the claims reference being had to the accompanying drawing in which—

25 Figure 1 is a side elevation of a device embodying the invention; Fig. 2, a vertical section through the same; Fig. 3, an end elevation; and Fig. 4, an enlarged detail showing the construction of a portion of 30 the head.

In the drawing 1 represents a suitable metal bushing having an externally screw-threaded lower end to engage a screw-threaded opening in the engine cylinder and 35 also formed with a hexagonal outer end or head by means of which the bushing may be screwed into the cylinder. The bushing is formed with an axial bore 2 extending therethrough which bore is enlarged in the 40 outer end or head of the bushing, forming a chamber 3 therein which is internally screw-threaded to receive a ring nut 4. Where the bore 2 and chamber 3 meet, an annular seat 5 is formed within the bushing and seated upon this seat is a packing ring or 45 collar 6 which forms a seat for an insulating plug 7 formed of porcelain or other suitable material, said plug being enlarged at its upper end within the chamber 3 to form 50 an annular shoulder to engage and seat upon the collar 6. The insulating plug is formed with an axial bore to receive a wire 8 which projects through the lower end of the plug and forms one electrode of the spark plug. 55 The other electrode is formed by a platinum

wire 9 secured within a hole in the lower end of the bushing 1 and bent at right angles toward the projecting end of the wire 8. The bore of the plug is enlarged at the upper end thereof forming an axial chamber there- 60 in to receive a short tubular insulating member 10 which fits therein and extends upward within the ring 4 beyond the upper end of the plug. The plug is securely held seated upon the collar 6 by the engagement 65 of the inner end of the ring 4 with the upper end of the plug. The bushing 1 and ring nut 4 thus together form a casing for inclosing and securely holding the insulating plug 7 and the tubular insulating mem- 70 ber 10.

A head 11 formed of porcelain, hard rubber, fibrous or other suitable insulating material is provided to close the upper open end of the casing, said head being formed 75 with a downwardly extending end 12 to fit within the ring 4 and to form an annular shoulder to rest upon the upper end of the ring. The head is also formed with an axial chamber 13 and a bore 14 extending laterally from the upper end of the chamber through a lateral extension or arm 15 on the head. The bore 14 is formed with a very deep internal screw thread 16 formed with a sharp cutting edge adapted to cut 80 into the insulation 17 upon an electrical conductor or wire 19 and securely hold the end of the wire within the extension 15 of the head. The wire is thus rigidly secured to the head by simply screwing one end of 85 the same into the extension and may be readily detached at any time. The inner end of the wire 19 rests against the upper end of the chamber 13 and to make an elec- 90 trical connection between said wire and the wire 8 forming the electrode of the spark plug, a coiled spring 20 is secured at one end to the upper end of the wire 8 with its opposite end in engagement with the wire 19. This spring when the head is in place, 95 is under compression and thus a good electrical connection is insured. The spring also exerts a force upon the upper end of the tubular insulating member 10 to hold the same in place. 100

The head 11 is detachably secured in place upon the ring nut 4 by means of a yoke 21 having inturned lower ends 22 to engage beneath the hexagonal head or flange 23 of the ring nut 4. Said head is thus free to 110

turn upon the ring nut as the inturned ends of the yoke only engage the flange and said yoke is carried by and turns with the head when said head is turned to bring the extension to the desired position. The yoke is held in place upon the head by means of inwardly extending pins 24 engaging vertical slots 25 in the sides of the head. The head is firmly clamped and yieldingly held by the yoke by means of a spring 26, one end of which spring is integral with the middle of the yoke and extending laterally therefrom, is folded backward upon itself in the form of a loop with the free end of the spring extending beneath the yoke in engagement with the surface of the head. The side of the head opposite the extension 15 is rounded so that the yoke may be turned upon its pivot pins 24 to disengage the in-turned ends 22 from beneath the flange 23. The spring loop 26 is bent upwardly to facilitate its sliding over the curved side of the head and also to form a handle by means of which the yoke may be turned. In this construction the electrical conductor is rigidly attached to the spark plug and held against all possibility of becoming loosened by vibration and the connection broken. The head may be turned to any desired position and may be quickly and easily detached for the purpose of inspecting the interior of the plug and the connections. The head while serving the purpose of a rotatable connection for the electrical conductor, at the same time closes the upper end of the spark plug and effectually protects the interior connections and insulating members.

It is obvious that changes may be made in the details of construction without departing from the spirit of my invention and I do not limit myself to the particular form and arrangement of parts shown.

Having thus fully described my invention what I claim is:

- 45 1. In a device of the character described, the combination of a casing having an open upper end, an insulating member in said casing, the terminals, and an insulating head fitting and free to turn within the upper end of said casing and adapted to receive and hold one end of an electrical conductor in proper relation to one of the terminals.
- 50 2. In a spark plug, the combination with a casing having an open upper end and an insulating member within and held by said casing, of an insulating head closing the upper end of the casing and having a lateral opening adapted to receive and hold the end of an electrical conductor, and means 55 for detachably holding said head in place adapted to permit the free rotation of the head relatively to the casing.
- 60 3. In a spark plug, the combination with a casing and an insulating member in said 65 casing, of an insulating head provided with

an opening to receive an electrical conductor and closing the upper end of the casing, and a member pivotally attached to the head adapted to be turned to detach said head.

4. In a spark plug, the combination with 70 a casing and an insulating member in said casing, of an insulating head provided with an opening to receive an electrical conductor, and a yoke pivotally attached to the head and engaging the casing for detachably 75 holding the head in place.

5. In a spark plug, the combination with a casing and an insulating member in said casing, of an insulating head free to turn upon and closing the upper end of the casing, means on the head for the attachment of an electrical conductor thereto, and a member carried by the head for yieldingly and detachably holding the head in place. 80

6. In a spark plug, the combination with 85 a casing and an insulating member in said casing, of an insulating head free to turn upon and closing the upper end of the casing and having a lateral extension formed with an internal screwthread, an insulated 90 electrical conductor screwed into said extension, and held therein by the engagement of the screw threads of the extension with its insulation and means for detachably holding said head in place. 95

7. In a spark plug, the combination with a casing adapted to be secured within an opening in an engine cylinder, of an insulating plug within the casing having an axial bore, an insulating head closing and free to 100 rotate within the outer end of the casing and provided with a lateral opening, an electrical conductor extending into said head through said opening, an intermediate tubular insulating member within the casing 105 spanning the gap between said plug and head, and an electrical conductor extending through the axial bore of the plug and the tubular member into said head.

8. In a spark plug the combination with 110 a casing adapted to be secured within an opening in an engine cylinder, of an insulating plug within the casing having a chamber in its outer end, an insulating head fitting within and free to turn upon the outer 115 end of the casing and provided with an internal chamber and with a lateral opening to receive an electrical conductor, an insulating member within the chambers of said plug and head and spanning the space between the same, an electrical conductor extending through said plug and insulating member, and means for detachably securing said head to the casing and permitting a free turning of said head upon the casing. 120

9. In a spark plug, the combination with a casing, of an insulating plug within the casing having an axial chamber in its upper end, a tubular insulating member within 125 said chamber projecting upward therefrom,

- an insulating head closing the upper end of the casing and having an axial chamber into which said tubular insulating member extends, said head also having a lateral opening to receive an electrical conductor, and a spring within said head engaging the tubular insulating member to hold the same within its chamber in the insulating plug.
- 5 10. In a spark plug, the combination of a casing, an insulating member within the casing, an insulating head closing the upper end of the casing and formed with a lateral opening to receive an electrical conductor, a yoke pivotally attached to the head and extending over the head with its ends detachably connected to the casing to hold the head in place, and a spring between the yoke and head carried by the yoke.
- 15 10. In a spark plug, the combination of a casing, an insulating member within the casing, an insulating head having a lateral opening to receive an electrical conductor, a flange at the upper end of the casing, a yoke pivotally attached to the head at each 20 side thereof and formed with inturned ends to engage beneath the flange, and a spring carried by the yoke.
- 25 11. In a spark plug, the combination of a casing, an insulating member within the casing, an insulating head having a lateral opening to receive an electrical conductor, a yoke pivotally attached to the head at each side thereof and formed with inturned ends to engage beneath the flange, and a spring carried by the yoke.
- 30 12. In a spark plug, the combination of a casing, an insulating head provided with an opening to receive an electrical conductor, a yoke extending over and pivotally attached to the head to engage the casing and hold the head in place, and a spring member comprising a loop extending laterally from the yoke intermediate its ends with the spring arm of the loop extending beneath the yoke in engagement with said head.
- 35 13. In a spark plug, the combination of a casing adapted to be secured within the spark plug opening of a cylinder, the terminals, an insulating member within the casing, a cap carried by the casing and forming a unitary part of the spark plug, said cap being rotatable in relation to the casing and closing the upper end thereof, and adapted to receive and hold one end of an electrical conductor in proper relation to one of the terminals.
- 40 14. In a spark plug, the combination of a casing adapted to be secured within the spark plug opening of a cylinder, the terminals, an insulating member within the casing, a cap carried by the casing and forming a unitary part of the spark plug, the cap closing the upper end of the casing, and adapted to receive and hold one end of an electrical conductor in proper relation to one of the terminals, and means for detachably holding said cap in place permitting 45 the same to be rotatably adjusted in relation to said casing.
15. In a spark plug, the combination with a casing adapted to be secured within the spark plug opening of a cylinder, of a member forming a unitary part of the spark plug rotatably adjusted in relation to the casing, said member having a connection for receiving an attachment, and yielding means for holding said member in its adjusted position.
- 70 16. In a spark plug, the combination of a casing adapted to be secured within the spark plug opening of a cylinder, an insulating member within the casing, a cap carried by the casing and forming a unitary part of the spark plug, and a contact extending through said insulating member, and having a portion arranged within the cap and completely inclosed thereby, said cap being provided with an integral lateral projection in operative relation to the contact and adapted to receive therewithin a terminal, and a connection between said cap and the casing permitting the cap to be secured to the casing in different positions of rotary adjustment.
- 75 17. In a spark plug, the combination with a casing adapted to be secured within the spark plug opening of a cylinder, an insulating member within the casing, a cap carried by the casing and forming a unitary part of the spark plug, said cap having a chamber, a contact extending through the insulating member having a portion arranged in said chamber and completely inclosed thereby, said cap having a screw threaded opening in operative relation to the chamber, and an insulated terminal extending through said opening into operative relation to the contact, and having a screw 80 threaded engagement with the opening.
- 85 18. In a spark plug, the combination of a casing adapted to be secured within the spark plug opening of a cylinder, an insulating member within the casing, a weather-proof cap on said casing and forming a unitary part of the spark plug, a contact in said casing completely inclosed by said cap, and the latter being provided with a terminal portion in operative relation to said contact adapted to receive therewithin a terminal, and a connection between the terminal portion and said terminal for securing the latter to the former and forming a weather-tight joint therewith.
- 90 19. In testimony whereof I affix my signature in presence of two witnesses.
- 100 ALBERT SCHMIDT.
